UNITED STATES PATENT OFFICE.

MARTIN L. HEINEKE, OF SPRINGFIELD, ILLINOIS, ASSIGNOR TO HEINEKE & COMPANY, OF SPRINGFIELD, ILLINOIS, A CORPORATION OF ILLINOIS.

THRASHING-MACHINE FEEDER.

1,419,926.

Specification of Letters Patent. Patented June 20, 1922.

Application filed January 26, 1918. Serial No. 213,849.

To whom it may concern:

Be it known that I, MARTIN L. HEINEKE, a citizen of the United States, residing at Springfield, county of Sangamon, and State 5 of Illinois, have invented new and useful Improvements in Thrashing-Machine Feeders, of which the following is a specification.

My invention relates to improvements in feeding attachments for thrashing machines. 10 In such attachments it has been common to associate with a feeding conveyor a set of band cutting knives and various devices for distributing the bundles of straw both longitudinally and transversely, in combination 15 with means for retarding some of the straw in a manner to prevent clogging the cylinder, and for stopping the conveyor when the retarded straw accumulates to such an extent as to tend to clog the feeders. But while it 20 has been recognized that in order to attain the best results, the bundles should be fed to the conveyor with the heads foremost, the fact has been largely overlooked that it is also desirable to not only deliver the straw 25 in such a manner that the cylinder will continuously receive all that it is capable of handling efficiently, but in such a manner that the cylinder teeth will strip the grain from the straw while the latter is being yielded 30ingly detained by the feeder, whereby the separation of the grain from the straw may be effected to the largest possible extent, while only the heads are engaged by the teeth of the cylinder, the teeth striking the grain 35 heads with a beating and also with a stripping effect, and removing the grain before the straw which carries such grain heads passes between the teeth of the revolving cylinder and those of the stationary concave. 40 The object of my invention is to provide a feeding attachment in which the bundles may be advanced and the bands cut in the usual manner, but in which the bundles will be more uniformly distributed than heretofore, and the grain fed to the thrashing cylinder 45 in a substantially continuous stream, and in such a manner that the straw will be drawn between the cylinder and the concave by the teeth of the cylinder itself, the feeder 50 operating at the delivery end to hold the straw under light tension while the grain heads are being stripped by the cylinder

teeth, and while the straw is being drawn between the cylinder and the concaves. The feeder is also provided with more sensitive 55 and efficient governing mechanism than has heretofore been employed, whereby the supply may be regulated within normal limits, and made substantially constant.

In the drawings:

Figure 1 is a longitudinal view of a thrashing machine feeder embodying the invention, the receiving end of the conveyor being broken away, and the feeder being illustrated in operative relation to the thrashing cylinder. 65

Figure 2 is a plan view of the same.

Figure 3 is a side elevation showing the feeder reversed in position as compared with Figure 1, and illustrating the driving and 70 governing connections on the illustrated side.

Figure 4 is a detail view in side elevation showing the relation of the crank operated serrated distributors to the band cutting knives. 75

Figure 5 is a plan view of the same.

Figure 6 is a sectional view, drawn on line 6—6 of Figure 4.

Figure 7 is a detail view, in side elevation, of the governing clutch, with parts of the 80 clutch operating wheel broken away.

Figure 8 is a plan view of the same.

Figure 9 is a sectional view, drawn on line 9—9 of Figure 8.

Like parts are identified by the same reference characters throughout the several views.

My improved feeder is adapted to deliver unthreshed grain to the cylinder 1 of an ordinary thrashing machine, the feeder being 90 preferably so located that it will deliver the grain to the cylinder on the downwardly moving side, the grain or unthreshed straw being preferably fed downwardly along an inclined plane, and reaching the cylinder 95 along a line a little above the horizontal plane of the cylinder shaft 2. The bundles are placed upon a feeding conveyor 5, the side chains of which pass over sprocket wheels 6, at the delivery end, said sprocket 100 wheels being supported by a shaft 7, which constitutes the driving shaft of this conveyor. The bundles are carried upwardly, at a slight inclination, to the delivery end of

this conveyor, from which they are discharged downwardly over a retarding head carried by the shaft 8, and having curved fingers 9, which catch and hold the straw from the under side while feeding it forwardly at a slower rate than the rate of travel of the conveyor 5. The retarder fingers 9 preferably curve backwardly in the circle of rotation, as shown. The structure of the conveyor itself, and of the retarder, as well as their arrangement with reference to the cylinder 1, conforms to ordinary practice, and further description is therefore deemed unnecessary. The band cutting blades 11 are also of ordinary construction, being mounted upon the shaft 12 and rotated above the delivery end of the conveyor, in a position to cut the bands of the advancing bundles.

The distributing rakes.

A set of distributing rakes are operatively supported across the path of the bundles which are advanced by the main conveyor 5. Each of these rakes is preferably formed from a strip of sheet metal, the side margins of which are obliquely bent and serrated to form rows of teeth 14 along each side of the central portion 15 of the metal strip, which central portion constitutes the back of the rake. Between the marginal teeth each rake bar is preferably provided with a curved blade 13, which projects below the teeth, and is not only adapted to cut bands which escape the blades 11, but is also adapted to cut and facilitate the delivery of tangled straw to the thrashing cylinder.

At their upper end these rakes are provided with bearing members 16, in which cranks 17, forming part of the crank shaft 18, are journaled. In the construction shown, the cranks are four in number, there being four rake bars with eight rows of rake teeth, and the cranks are so arranged that adjacent cranks in the series are disposed at an angle of 90 degrees to each other. The crank shaft is rotated in the direction indicated by the arrow in Figure 1, and the connected ends of the rakes therefore travel a circular path, in which they move downwardly in the direction of the band cutting knives 11, and then rearwardly and downwardly in the direction of the cylinder, after which they are carried upwardly and forwardly to complete the cycle of rotation.

When the upper end of a rake approaches the band cutting knives 11, the latter pass between its teeth 14, and the crank shaft 17 is preferably so located that at the point of nearest approach of any given rake to the band cutter, the extremities of the band cutting teeth 11 will pass through notches 20 formed in the upper end of the back of the rake. The band cutting blades are therefore adapted to cut through any material which

may become lodged between the teeth at the upper ends of the rake, whereas the rake also serves to clear the blades of the band cutter of any material that may be caught and carried around by the outer portions of the teeth thereof. It is therefore impossible for straw to wind around the band cutter shaft to such an extent as to render the band cutter inoperative. The rake teeth preferably have front margins extending at right angles to the back of the rake, and these margins may have sharp cutting edges, if desired. The rear margin of each tooth is preferably inclined, as shown, whereby retraction of the straw during the retractive movement of the rake is avoided, the teeth being adapted to slide over the straw during the retractive stroke.

The lower end portions of the rakes overhang the retarder, and are supported from a cross shaft or bar 25 by arms 26, rigidly connected with this bar and projecting rearwardly therefrom. The rear end of each arm is connected with one of the rakes by one or more links 27, and one or more arms 26 may be employed to support the lower end of each rake. The links allow the rakes to reciprocate toward and away from the cylinder when the crank shaft 18 is rotated. The shaft 25 is journaled in the walls of the housing 28, and is adapted to oscillate in its bearings, thereby allowing the lower ends of the respective rakes to be lifted, or swung rearwardly about the axis of the crank shaft as a center, under pressure of the grain or unthreshed straw, when the latter accumulates in the space between the retarder and the rakes, or between the rear end of the main conveyor 5 and the rakes.

The function of the rakes is to deflect the material carried by the main conveyor downwardly over the delivery end thereof to the retarder, and to feed the material progressively from the retarder, or from the space above the retarder, to the thrashing cylinder, the rakes working in the straw from the top downwardly with a combing action, and each rake tending to deliver a measured quantity of unthreshed grain to the cylinder. Inasmuch as all the rakes in the series operate successively at intervals represented, in the construction shown, by the time required for the crank shaft to rotate a one quarter turn, it is obvious that the burden upon the thrashing cylinder will be quite evenly distributed, and will be received by different portions of the cylinder successively. For example, assuming that straw is being delivered to the cylinder by the left hand rake, it is obvious that with the construction shown, the next rake to the right thereof will commence to advance the straw while the feeding operation performed by the first rake is being completed, and the operation of the second rake will be succeeded by that of the third rake.

and this in turn will be succeeded by the feeding operation performed by the fourth rake, after which the cycle of feeding operations will again be resumed by the first rake 5 above mentioned. By this method of feeding, I secure a desired advantage over a feeder, in which alternate rake bars operate in unison to feed the straw simultaneously to the cylinder.

10 *Means for controlling the rake pressure.*

It has already been stated that the shaft 25 is adapted to oscillate, as illustrated, in its housing bearing. One end of the shaft 15 projects through the housing wall, and is provided with an exterior arm 30 connected by a spring 31 and adjusting screw 32, with a bracket arm 33 projecting from a slide 34, mounted in vertical guide ways 35 on the exterior wall of the housing, as best shown in Figure 3. The slide is vertically adjustable by means of a screw shaft 36, provided with an operating crank 37, and the arm 30 is adapted to bear upon the top of the slide 34, 20 which limits its downward movement under the tension of spring 31. A thumb nut 37' on the adjusting screw 32 regulates the tension of the spring 31, and the slide 34 is raised or lowered in accordance with the requirements of any given thrashing operation, to increase or diminish the normal distance between the lower ends of the rake bars and the retarder. It is obvious that the 25 vertical adjustment of the slide 34 will have no effect upon the tension of spring 31, since bracket arm 33 is connected with said slide, and the arm 30 normally bears on the upper end of the slide. When the quantity received between the rakes and the retarder is sufficient to lift any one of the rakes, arm 30 will, of course, swing upwardly from its bearing upon the upper end of slide 34, but this upward movement will be opposed by the tension of spring 31, the resistance of the 30 spring increasing in proportion to the movement, whereby the downward pressure of the rakes upon the straw will be correspondingly increased, thereby increasing the effectiveness of the rakes to feed the straw to the cylinder within the range of its capacity.

Inasmuch as each rake has the form of an inverted pan, the side margins of which have projecting teeth extending obliquely with reference to the back of the pan and to the teeth on the other margin, it is obvious that teeth formed as herein described will not only engage the straw effectively, but, owing to the lateral extension of the back, the depth of penetration by the teeth will be limited 35 and the rake will be positively lifted in direct proportion to the accumulation of material underneath it. The controlling mechanism now to be described is thereby made much more positive in its action than would be the case if each set of rake teeth were lo-

cated upon an independently movable bar of approximately the same thickness as the teeth.

Conveyer control.

70

Whenever the straw accumulates within the feeding space, provided between the delivery end of the main conveyor and the retarder on one side and the rakes on the other side, to a point where the capacity of the cylinder is overtaxed, or a clogging of the conveying and feeding mechanism threatened, the lower ends of the rake bars will, of course, be lifted beyond their normal range of swinging movement, as controlled by the exterior arm 30 and spring 31. When this occurs, it is desirable to stop the main conveyor 5 in order that no more bundles may be delivered until the rakes and the retarder have relieved the congestion. The spring 31, 85 by pulling downwardly on the arm 30, applies resilient downward pressure to the arms 26 within the housing through the oscillatory shaft 25, (see Fig. 1), thereby causing the lower or inner ends of the rake bars 90 to push downwardly upon the material above the retarder, in resilient pressure relation to such material. When the conveyor stops, as hereinafter explained, the rakes and the knives 13, carried thereby, will continue to push the congested material from 95 above the retarder toward the thrashing cylinder, the knives cutting tangled material, and the upper portion of the congested mass being thus cut, and fed forwardly as rapidly as the cylinder can take care of it. To accomplish this, I employ a clutch, through which motion is transmitted to the main conveyor 5, and which may be automatically released whenever the rakes are lifted by the 100 straw beyond a predetermined limit. Various clutch mechanisms for this purpose have been designed, but it is very desirable that the clutch mechanism employed for this purpose should be instantly responsive and 105 highly sensitive, but positive in its action, both for releasing the main conveyor and for again connecting it with the power transmitting mechanism. I have therefore designed a special form of clutch mechanism adapted 110 to answer these requirements, and this will now be described.

Motion transmitting connections and clutch mechanism.

120

It will be observed, in Figure 3, that the band cutter shaft 12 is directly driven from the cylinder shaft 2, by means of a belt or chain 40, operating over suitable pulleys or sprocket wheels, mounted on these shafts. Another belt or chain 41 transmits motion from the band cutter shaft 12 to the crank shaft 18. A third belt or chain 42 transmits motion from shaft 12 to a stud shaft 43, having a pinion 44 fast thereon, and adapted 125

130

to continuously drive a gear wheel 45, loosely mounted upon the shaft 7 which drives the main conveyor 5.

Gear wheel 45 is provided with a set of laterally projecting studs 47, each of which carries a roller 48. The studs 47 are equidistant from the axis of the gear wheel, and any one of the rollers 48 may be utilized to transmit motion to the shaft 7 through a clutch dog 50, pivotally connected at 51 with a collar 52, mounted upon and keyed to the shaft 7, or otherwise secured to rotate therewith. The clutch dog 50 is provided with an arm 55, which is adapted to be swung into the circular path traversed by the rollers 48, the body of the clutch dog 50 being located beyond the ends of these rollers and stud shafts 47.

The outer end of the collar 52 is provided with a flange 57'. A spring 58 is secured to this flange and bears upon the clutch dog in a manner to normally hold it in the position in which it is illustrated in Figure 7, with its projection or arm 55 adapted to be engaged by any one of the rollers 48. The flange 57' is fitted to a recess in the side of a ratchet disk 57, which is loosely mounted on shaft 7, but tends to rotate with it by friction on the shaft. A stud 60 carried by the disk 57, engages in a slot 61 in the clutch dog, and is adapted to swing the dog inwardly toward the shaft 7 to carry arm 55 out of the path traversed by the rollers 48, whenever disk 57 is relatively rotated in a direction opposite that in which gear wheel 45 rotates. The bearing surface of the projection or arm 55 is rounded, and the outwardly swinging movement of dog 50 is limited by stud 60, in such a manner that the dog will bear only against the inner portion of the engaged roller 48. The arrangement is such that it is merely necessary to stop the rotation of disk 57 in order to release the clutch dog from the engaged roller 48, since the roller will tend to carry the dog around with it, but the pin 60 will push the dog inwardly toward the shaft, thus causing it to oscillate upon its pivotal connection with the shaft at 51. But unless the disk 57 is held against rotation, the arm or projection 55 will have a sufficient bearing against the engaged roller 48 to enable the latter to transmit motion through the dog to the shaft 7, thereby causing the latter to rotate with the gear wheel 45.

Disk 57, being loose on shaft 7, normally tends to revolve with it. But in order that this rotative motion may be automatically arrested, I provide the periphery of the disk 60 with a set of teeth 65, each of which is adapted to be engaged by a latch projection 66, carried by a swinging arm 67, which is pivoted to the housing at 68, and has its range of movement limited by a stop pin 69, operating in a notch 70 formed in a sleeve

71, formed on the pivoted end of the latch arm 67. The pivot stud 68 is stationary, and the stop pin 69 extends through it, the lower end of this pin being connected with the latch arm 67 by a spring 72, whereby the latch 66 is normally held in retracted position, as shown in Figure 7.

When the quantity of material delivered into the path of the rake teeth 14 becomes excessive, thereby lifting the lower end of any rake bar beyond the predetermined limit above referred to, this swinging movement of the rake bar will be transmitted through arm 26, shaft 25, exterior arm 85 and adjustable link rod 86, to raise latch arm 67 until latch head 66 is in the path of the teeth 65 on the clutch controlling disk 57. Thereafter, as soon as one of the teeth 65 engages the latch head 66, the motion of the disk will be stopped, and it will immediately retract clutch dog 50, since the effect will be substantially the same as if this disk were rotated in a direction opposite that in which gear wheel 45 is being continuously rotated. But inasmuch as the motion of shaft 7 is derived from gear wheel 45 through the dog 50, it is obvious that a retraction of the dog arm 55 from the roller 48, which it engages, will allow shaft 7 to come to rest, whereupon the movement of the main conveyor 5 will immediately cease.

The retarder shaft 8 is continuously driven from gear wheel 45 through a belt or chain 90, which runs over suitable pulleys or sprocket wheels connected with the gear wheel 45 and with shaft 8, respectively. Therefore the retarder will continue to rotate. The band cutting knives will also continue to rotate, and the rakes will continue to reciprocate until the congestion of material beyond the delivery end of the main conveyor has been relieved to a point where the lower ends of the rakes are again operating within their range of normal feeding movement. When this occurs, arms 65 will have swung downwardly, and latch head 66 will have been retracted by gravity and by the reaction of spring 72. As soon as the latch is released the reaction of spring 58 causes disk 57 to rotate upon shaft 7 sufficiently to swing the clutch dog 50 outwardly to motion transmitting position, whereupon motion will be again transmitted to the conveyor 5.

It will be observed that link rod 86 extends through an aperture in latch bar 67, and is provided with a head 75, normally supported at a short distance below the latch bar. This allows arm 65 to be raised to some extent before it actuates latch arm 67, and provides for the normal range of swinging movement permissible in the rake bars under tension of spring 31, as above described. It will also be observed that the link rod 86 is provided with a sleeve 77, to

which the arm 85 is directly connected, this sleeve being adapted to slide upwardly on the rod 86 against reactionary pressure exerted by a compression spring 78, interposed between the upper end of this sleeve and a thumb nut 79. Another thumb nut 80 acts as a stop to limit the downward movement of the sleeve. The two thumb nuts allow the range of sleeve movement to be varied in accordance with variations in the slide 34.

Operation.

The operation of the feeder is as follows:

The bundles of unthreshed grain placed upon the conveyor 5 are carried underneath the rapidly revolving band cutter knives 11, whereby the bands are cut. A partial distribution of the bundles is also secured, since the band cutting blades move through the straw with a stripping action, and tend to carry the top of the bundle forwardly at a more rapid rate than the conveyor travels. The material is thus carried into the path of the reciprocating rakes, the teeth 14 of which engage in the straw and push it downwardly, these teeth also operating with a combing action, whereby the straw is held and fed longitudinally, and whereby it is additionally distributed along longitudinal lines. Where the bundles are properly placed upon the conveyor 5 with the heads foremost, it is obvious that the heads of grain will reach the cylinder teeth in advance of the butts, it being to some extent delayed by the more slowly moving retarder and the teeth 14 of the rakes, while the rapidly revolving cylinder teeth break the husk, and strip the grain from the heads, subsequently pulling the straw forwardly between the teeth of the rakes and of the retarder as rapidly as the cylinder is able to receive it. While this action is proceeding, with reference to the of the rakes which has passed a quantity of straw forwardly to the cylinder, the next adjacent rake is acting in a similar manner to push another quantity of straw forwardly, as above explained. Where the straw is dry and brittle it can be fed to the cylinder rapidly, and in such cases the feed controlling slide 34 is moved upwardly, and clutch controlling sleeve 77 is also adjusted upwardly to allow the rakes to operate at a considerable distance from the retarder. But for tough straw or wet straw, an opposite adjustment of slide 34 and sleeve 77 is required, whereby the field of swinging rake movement is brought closer to the retarder. The quantity of straw permitted to be delivered to the cylinder will therefore be more limited.

Figures.

4. A feeder for threshers comprising the combination of a main conveyor, a retarder

located beyond and below the discharge end of the conveyor, a set of rakes inclined downwardly from a point substantially above the discharge end of the conveyor to a point substantially above the retarder, means for reciprocating said rakes, supporting means for the lower ends of the rakes adapted to permit their upward movement extended above the paths of normal reciprocation by said reciprocating means, and means operating independently of the speed of movement of said parts and adapted to be positively operated from the rakes during their extended upward movement to control the movement of said main conveyor independently of that of the retarder.

2. A threshing machine feeder including the combination of a main conveyor, a rotary retarder located beyond and below the delivery end of the conveyor in a position to receive material therefrom, a set of reciprocating rakes inclined downwardly across the plane of said main conveyor and along the line of travel of material on the retarder and provided with teeth adapted to positively engage and advance the material, means for supplying the lower ends of the rakes in resilient pressure relation to such material, means for driving the rakes continuously, and means controlled by the rakes when lifted out of their normal paths in opposition to said resilient pressure for regulating the movement of the main conveyor independently of the speed conditions of the driving mechanism.

3. A threshing machine feeder including the combination of a main conveyor, a rotary retarder located beyond and below the delivery end of the main conveyor in a position to receive material therefrom, a set of reciprocating rakes inclined downwardly across the plane of the main conveyor and normally converging along the line of travel of the conveyor on the retarder, said rakes having teeth adapted to positively engage and advance the material, means for supporting the lower ends of the rakes in resilient pressure relation to such material, means for driving the rakes and the retarder continuously, and means for utilizing lifting movement of the rakes in opposition to said resilient pressure to regulate the movements of the main conveyor when the rakes have been lifted a predetermined distance out of their normal paths of reciprocation.

4. A feeder for threshers comprising the combination of a main conveyor, a retarder located and adapted to receive support and retard the movement of material delivered from the said conveyor, feeding rakes having teeth adapted to positively engage and advance the material, said rakes being located to receive material from the conveyor between them and the retarder and having transversely extending surfaces to receive

- the pressure of such material and limit the depth of rake penetration therein, means for actuating the rakes to distribute and advance material from the upper surface of
- 5 a mass detained by the retarder, connections permitting the delivery ends of the rakes to be lifted out of their normal paths of reciprocation to enlarge the space between them and the retarder under pressure of
- 10 massed material in such space, said connections adapted for transmitting extreme lifting movements of the rakes independently of speed conditions to control the movement of the main conveyor.
- 15 5. A feeder for threshers comprising the combination of a main conveyor provided with clutch controlled driving connections, a retarder located to receive material from the conveyor and advance it with retarded
- 20 movement for final delivery, distributing devices adapted to receive the material between them and the retarder and to accelerate deliveries from the upper portions of such material, means for supporting the
- 25 distributing devices for movement in normal paths, said supporting means being adapted to resiliently yield to allow the distributing devices to operate along paths more distant from the retarder and with in-
- 30 creased pressure upon the material when the space between such devices and the retarder becomes congested, and connections operative independently of the speed of the parts adapted to transmit said yielding
- 35 movement in its final stages to release the main conveyor clutch after said space has been materially enlarged by the initial yielding movement of the distributing devices.
6. A feeder for threshers comprising the
- 40 combination of a main conveyor provided with clutch controlled driving connections, a retarder located to receive material from the conveyor and advance it with retarded movement for final delivery, distributing devices
- 45 adapted to receive the material between them and the retarder and to accelerate deliveries from the upper portions of such material, means for supporting the distributing devices for movement in normal paths, said
- 50 supporting means being adapted to resili-
- 55 idently yield to allow the distributing devices to operate along paths more distant from the retarder and with increased pressure upon the material when the space be-
- 60 tween such devices and the retarder becomes congested, and connections operative independently of the speed of the parts adapted to transmit said yielding movement in its final stages to release the main conveyor
- 65 clutch after said space has been materially enlarged by the initial yielding movement of the distributing devices, said connections being adjustable to predetermine the extent of said yielding movement permissible without releasing the main conveyor clutch.
7. A feeder for threshers comprising the combination of a main conveyor provided with a driving clutch, cooperating means for preventing massed deliveries of material to the thresher by retarding the lower portions of such material, cooperating rakes adapted to positively and progressively tear away and advance acceleratingly the upper portions of massed material so retarded, means for resiliently pressing the delivery ends of such rakes against the material while allowing them to yield under progressively increasing pressure against such material, and connections operative independently of the speed of the parts for transmitting extreme
- 80 yielding movements of the delivery ends of the rakes to release the clutch and stop the conveyor after allowing a substantial increase in the distance between said ends of the rakes and the retarding means.
- 85 8. A feeder for threshers comprising the combination of a main conveyor provided with a driving clutch, cooperating means for preventing massed deliveries of material by retarding the lower portions of such mate-
- 90 rial, a cooperative rake normally inclined toward the retarding means and its delivery end and adapted to positively advance and accelerate the movement of the upper portions of such material relatively to those
- 95 portions which are held by the retarding means, a yielding support for the delivery end of said rake, and connections between said support and the clutch adapted to automatically regulate the movement of the
- 100 main conveyor independently of the feeding movement of the rake and of the speed of the driving connections, said clutch connections being operative during the final yielding movement of said support after allowing a material enlargement of the space be-
- 105
9. A feeder for threshers comprising the combination of a main conveyor provided with a driving clutch, cooperating means for
- 110 preventing massed deliveries of material by retarding the lower portions of such material, a cooperative rake normally inclined toward the retarding means and its delivery
- 115 end and adapted to positively advance and accelerate the movement of the upper portions of such material relatively to those portions which are held by the retarding means, a yielding support for the delivery end of said rake, and connections between
- 120 said support and the clutch adapted to automatically regulate the movement of the main conveyor independently of the feeding movement of the rake and of the speed of the driving connections, said clutch connections
- 125 being operative during the final yielding movement of said support after allowing a material enlargement of the space between the rake ends and the retarding means, said connections being also adjustable to vary the
- 130

degree of said yielding movement permissible before regulating the conveyor movement.

10. A thrashing machine feeder including the combination of upper and lower distributing and feed regulating mechanisms adapted to advance the material at differing speeds with increasing pressure and volume capacity as the quantity of material increases, a main conveyor adapted to deliver material between said feed regulating and distributing mechanisms, and means controlled by excess quantities of material so delivered for interrupting the movements of the main conveyor independently of the speed conditions of the other parts while allowing the feed regulating and distributing mechanisms to continue in operation.

11. A thrashing machine feeder including the combination of resiliently opposed upper and lower feed regulating and distributing mechanisms, one provided with holding teeth and the other having teeth adapted to positively engage and tear material away from a mass partially detained by the holding teeth, a main conveyor adapted to deliver material between the feed regulating and distributing mechanisms, driving connections for said conveyor and for the feed regulating and distributing mechanisms, and means operative independently of speed conditions in said driving connections and controlled by excess quantities of material delivered by the main conveyor for disconnecting such conveyor while allowing the feed regulating and distributing mechanisms to continue in operation.

12. The combination with the thrashing cylinder of a thrashing machine, of a main conveyor, a rotary retarding device disposed to allow the material to pass across it from the conveyor to the cylinder, means for rotating the retarding device to advance material at less speed than that of the conveyor, a set of feeding devices disposed to receive the material from the conveyor between them and the retarding device and to positively push such material toward the cylinder, means for applying resilient pressure to said feeding devices and for progressively increasing such pressure in proportion to the degree of separation of such devices from

the retarder, and means operating independently of the speed of the parts for utilizing a maximum separating movement of such feeding devices to regulate the movement of the main conveyor while allowing the cylinder, the feeding devices and the retarder to continue to operate without diminution of speed.

13. In a feeder for threshers the combination with a main conveyor provided with a driving clutch, a lever adapted when actuated to effect a release of said clutch, a rod provided with means for engaging and actuating said lever after a predetermined degree of movement from normal position, a set of reciprocatory feeding rakes in cooperative relation to the main conveyor and supported for swinging movements under pressure of material delivered by the main conveyor, and connections for transmitting said swinging movements to said rod, whereby swinging movements of the rakes in one direction may be transmitted to the rod and during the final movement of the rod to the clutch releasing lever, said clutch being adapted to automatically reengage when an opposite movement of the rakes releases said lever.

14. In a feeder for threshers the combination of a main conveyor provided with a normally operative driving clutch, a cooperating set of auxiliary feeders provided with teeth adapted to positively engage and advance material from the main conveyor, an oscillatory shaft having projecting arms linked to the delivery end portions of said auxiliary feeder, a clutch releasing lever, a lever actuating rod adapted for limited independent movement, an arm connected with said oscillatory shaft and adjustably connected with said rod, and a spring adapted to oppose oscillatory movement of said shaft in a direction to actuate said rod and lever for a clutch releasing operation.

In testimony whereof I affix my signature in the presence of two witnesses.

MARTIN L. HEINEKE.
